UNITED STATES PATENT OFFICE.

ANTOINE J. LANGEIER, OF PROVIDENCE, RHODE ISLAND.

HEEL-MACHINE.

SPECIFICATION forming part of Letters Patent No. 388,884, dated September 4, 1888.

Application filed August 27, 1887. Serial No. 248,097. (No model.)

To all whom it may concern:

Be it known that I, ANTOINE J. LANGEIER, of Providence, in the State of Rhode Island, have invented a new and useful Improvement 5 in Heel-Machines, of which the following is a specification.

My invention relates to additional improvements upon the heel-machines secured to me by Letters Patent of the United States Nos. 317,149 and 331,412; and it consists in improved devices for operating the cutting-plungers and the pasting device in an improved heel-nailing attachment, and in minor details of the construction of the machine.

Figure 1 is a front elevation of my improved heel-machingne. Fig. 2 is a side elevation of the same. Fig. 3 is a rear elevation with one of the paste-cups shown in section. Fig. 4 is a top view with one of the cups removed in order to more fully illustrate the subjacent mechanism. Fig. 5 is a detail plan view of the revolving carriers. Fig. 6 shows a vertical section of the same. Figs. 7 and 8 are detail views of a portion of the mechanism for operating the carriers. Figs. 9, 10, and 11 are detail views of the clutch mechanism. Figs. 12, 13, and 14 are detail views of the mechanism for engaging and disengaging the cutting-plungers with and from their operating mechanism. Figs. 15, 16, 17, and 18 are detail views of the cutting and pasting mechanism. Figs. 19, 20, 21, 22, 23, 24 and 25 are detail views of the nailing mechanism. Fig. 26 is an enlarged detail view of the pasting mechanism. Fig. 27 is an enlarged detail view of the heel-disengaging mechanism.

In the accompanying drawings, A is the supporting-frame of the machine, and B B' the table in which the heel-lift cutters C C' are securely held by means of the flanges D D'.

To the upward extension of the frame A, which branches laterally in opposite directions, are secured the sliding heads E E', to which an up-and-down movement is imparted by means of the two-movement cam F, which is secured to the loose gear G, held upon the main shaft H, and from which operative connection is made to the sliding heads E E' by means of the lever I, pivoted to the lug a, extending upward from the shaft-bearing standard J, and provided with a friction-roller adapted to enter the groove c of the cam, the adjustable

connecting-rod K, arm L, secured to the middle of the rock-shaft L', which is held in the opposite bearings d d, and the engaging arms 55 M M', secured to the opposite ends of the rock-shaft, and which enter the slots b in the straps N of the sliding heads. The sliding heads E E' are represented in Figs. 1, 2, and 3 as at the middle parts of their stroke, and are thrown into 60 operative engagement with the arms M M' or disengaged therefrom by means of the horizontally-moving levers e, attached to the lower end of the upright rods j j', to the upper end of which are secured the horizontal arms f f', 65 which are forked at their outer ends, as shown in Fig. 14, to engage with the head g of the sliding bars h, and the sliding bolts i, which pass transversely across the slot b, are rigidly connected to the sliding bolts h by means of 70 the link k and nuts l l.

At the lower end of the rods j j' are placed the torsion-springs m, which serve to move the bolts i back out of engagement with the arms M or M'. When either of the bolts i is 75 thrown forward, the vibrating movement of the arms M or M', as the case may be, will be imparted to the sliding head, and upon the withdrawal of the bolt by means of the action of the torsion-spring m, the vibration of the 80 arm M or M' will continue without imparting corresponding movement to the sliding head. Thus, while the arms M M' are to have a continuous vibrating movement imparted to them from the cam F, the specific reciprocating 85 movement imparted to either of the sliding heads E or E' will be under the control of the operator of the machine.

The levers e e are arranged to be moved horizontally by the foot of the operator, and 90 when the bolt i is in engagement with the vibrating arm, the lever e, which serves to operate the said bolt for engagement, will be held in its engaging position by means of a suitable catch-spring, w, which catches over the outer 95 end of the lever e, so that upon the subsequent release of the lever e from the spring-catch w by pressing the said catch back by the foot of the operator the resilience of the coiled spring m will serve to throw back the 100 lever e and withdraw the bolt i, so that the further up-and-down movement of the sliding head of the cutter will cease.

Upon the lower end of the hollow shank g,

which is secured by any suitable means to the sliding head, is secured the cutting-plunger P, which is made in the form of a heel section, as shown in Fig. 18, which shows an under side view of the cutting-plunger and its attached accessories, the plunger being made to screw against a shoulder, r, and loosely upon the plunger P is placed the holder Q, which is made to fit the sides of the heel-shaped plunger, and the downward movement of the holder under the action of the springs s s, which rest against the flange m⁵ of the hollow shank q, is limited by the stop-screws n n, which pass through the base of the ears o o and rest against the upper edge of the cutting-plunger, the springs being bent in bow form, with their ends forked and resting upon the pins p p, which are tightly secured to the ears o o. The shank q is centrally bored to receive the sliding paste-tube R, to the lower end of which is secured the valve-holder t. The tube R also serves as a forcer to carry the heel-lifts downward through the cutter and into the carrier-openings. The valve u, which rests on the conical valve-seat v, is provided with a stem, w, loosely held in a suitable guide at the point x within the bore of the tube. The valve-holder t is provided with a flange, f', which at the upper position of the cutting-plunger rests against the shoulder g' at the lower end of the cylindrical shank q, being held thereto by means of a weighted lever device, to be hereinafter described. The flange f' is also provided at its lower side with the clearing-recesses h' h' h' h'.

The tube R passes upward into the paste-cup T through a closely-fitting opening, i', and is provided near its upper end with the lateral perforation j', through which the paste is to enter the tube from the cylindrical portion t⁵ of the paste-cup. Over the tube R is placed the sliding sleeve l', which is attached to a spiral spring, l', secured to the closed head m' of the tube. The paste-cup T is secured to the upper end of the sliding head by means of the bracket n', to the inner side of which, at the point o', is pivoted the lever p', provided with a downwardly-projecting arm, q', at the extremity of which is placed the adjusting-screw r'. The lever p' is connected to the arm s', which is also pivoted to the bracket n' by means of the pin t', passing through the bracket, by means of the link u', and upon the outer end of the arm s' is placed the adjustable-weight v'. The arm w' is also attached to the pin t', and is connected to the paste-tube R by means of a clamp, x', which is pivoted to the end of the arm w', so that a vibrating movement imparted to the arm w' will serve to impart a direct reciprocating movement to the paste-tube R.

To the top of the frame A, at each side of the machine, are secured flat springs, U, which serve to actuate the paste-tube upon the downward movement of the sliding head.

The two upright shafts V V' are operatively connected to each other by means of the gears

W W, as shown in Fig. 5, the said gears being located at the lower ends of the said shafts under the base X of the frame of the machine. 70

Upon the upper end of the shaft V is secured the two-armed carrier-plate Y', provided with openings adapted to receive the removable bushings y', which are provided with an opening, z', made in heel form; and upon the upper end of the shaft V is secured the two-armed carrier-plate Y, which is preferably made thicker than the plate Y', and is also provided with bushings y', having an opening, z', of greater area than that of the bushings of the carrier-plate Y'. The table B above the carrier-plate Y is provided with the cutter C, which is made in form and size to correspond with the receiving-opening z' of the carrier Y, located under the same, and the table B' above the carrier-plate Y' is provided with the cutter C', which is made in form and size to correspond with the receiving-opening of the carrier Y'.

The upright shafts V V' are driven from the shaft H by means of the wheel B², provided with the stud b², and the wheel C², provided with openings c² to receive the stud, whereby upon each revolution of the shaft H the wheel C² and shaft D', upon which it is secured, will be rotated for one-quarter of a revolution, and upon the forward end of the shaft D' is secured the bevel-gear d², which is provided with twice the number of teeth in the bevel-pinion e², which is secured to the upright shaft V', so that the carriers upon the upper ends of the shafts V V' will be rotated for one-half a revolution at every revolution of the shaft H.

At the forward end of the shaft H is placed the crank-disk E', from which connection is made to the toggle-levers F' G' by means of the connecting-rod H'.

To the upper end of the toggle-lever G' is pivoted the head f², at the upper end of which is placed the rubber cushion g², and over the pivoted head f² and cushion g² is placed the sliding head H², to the upper end of which is secured the plunger I', which serves to compress the heel in the coincident heel-receiving chambers of the carriers and to force the heel upon the nails while the same are being held and carried forward by means of the holding and cutting jaws a³.

The pivot-pin h² of the toggle-lever joint is extended to form an arm, J', from the outer end of which connection is made with the vibrating lever K' by means of the connecting-rod L', so that the lateral movement of the toggle-lever joint will serve to impart an up-and-down movement to the end of the lever K'. The lever K' is pivoted to the inwardly-projecting bosses a² on the frame of the machine, and is provided with the attached cam-shoe i', which operates against the forward end of the bell-crank lever j² to cause the proper closing movement of the jaws a³ upon the wire to form the nails.

To the forward end of the bell-crank lever j² is pivoted the sliding head l', which is slot-

ted to receive both the bell-crank lever and the lower edge of the lever K' , the pivot m^2 passing through the end of the said lever and the ears $n^2 n^2$ of the sliding head. Upon 5 the back of the lever K' is attached the toe o^2 , which, by striking against the lip p^2 at the upper end of the bell-crank lever, imparts an upward movement to the sliding head l^2 . The bell-crank lever j^2 is pivoted between two 10 ears, q^2 , which are removably attached to a portion of the frame.

To the upper end of the rod r^2 , which is held in a fixed guide, s^2 , is attached the bracket t^2 , to which is secured the bifurcated arm u^2 , 15 the outer ends of which are provided with suitable clamps, $v^2 v^2$, for engaging with two separate wires running from the reel k^2 and feeding the same downward to the nail forming and inserting devices, and the hub w^2 of 20 the lever K' is provided with the parallel slots x^2 , to provide for a straight downward path for the wire from the reel to the feeding-clamps of the arm u^2 .

Within the cavity y^2 of the sliding head l^2 25 is secured the wire separating and holding jaws a^3 , which are loosely secured therein by means of the transverse pin b^3 , which passes through the middle upper portion or shank of the jaws, the lower portion of the jaws being 30 extended laterally in opposite directions from the shank and provided with the cavities $c^3 c^3$, the lower ends of which terminate in sharpened edges $d^3 d^3$, made in angular form, by means of which the wires are separated into 35 the proper length to form the nails and are properly pointed for insertion into the leather without the employment of an awl. The sides of the holding and cutting clamps $a^3 a^3$ are brought together to cut off the wire by means 40 of the wedge form of the lower end of the jaws and the correspondingly-contracted form of the opening e^3 in the plate f^3 . The plate f^3 , which is secured to a portion of the frame 45 A , serves to resist the upward movement of the heel when subjected to the compressing action of the plunger I' .

The rod r^2 , to which the feeding-clamps $v^2 v^2$ are connected, is operated in its vertical movement by means of the inclined cams g^3 upon 50 the periphery of the upper carrier, Y , as shown in Fig. 5, and a downwardly-acting spring, r^5 , which is secured to the frame and rests upon the top of the bracket t^2 , and the downward movement of the feeding-clamps is regulated 55 by means of the adjusting screw h^3 .

In order to provide for the disengagement of the finished heel from the carrier, I secure a stationary cam, i^3 , to the frame A and attach to the said frame a bracket, j^3 , which 60 loosely holds the rod k^3 , and upon the said rod, above the bracket, is secured the arm l^3 , provided with a hollow head, m^3 , in which is placed the sliding bar n^3 , provided with a stem, o^3 , upon which is placed the spiral spring p^3 , 65 the bar n^3 being held within the head m^3 by means of the screw q^3 and a slot in the side of the enlarged portion of the bar. At one side of

the lower end of the bar n^3 is formed the arm r^3 , which is adapted for engagement with the cam i^3 , causing the upper end, s^3 , of the bar n^3 70 to rise into the heel-opening of the carrier, and thus force the finished heel out of the same. The arm r^3 is caused to rest against an adjacent portion of the frame or a suitable fixed stop by means of the torsion-spring t^3 , one end of 75 which is secured to the bracket j^3 and the opposite end to the adjustable collar u^3 upon the rod k^3 . Suitable movement is imparted to the arm r^3 from the carrier by means of the outwardly-projecting arm v^3 , which arm is adapted 80 to engage with an interior shoulder, w^3 , of the carrier. (Shown in Fig. 6.) The shaft H is operated from the loose revolving gear G by means of the sliding clutch-sleeve x^3 , which is partially inclosed in the bearing y^3 of the 85 standard J and engages with the opposite clutch member, z^3 , which is firmly keyed to the gear G , and in order that the clutch may be automatically disengaged at each complete revolution of the shaft H , I provide at the 90 rear end of the sliding clutch-sleeve x^3 a flange, b^4 , provided on its forward face with an inclined spur, c^4 , as shown in Fig. 9, and loosely upon the clutch-sleeve x^3 and partly within the enlarged bore of the bearing-standard J is 95 placed the sleeve d^4 , which is provided with a groove, e^4 , which engages with the point of the screw f^4 upon the standard J , (see Fig. 11,) whereby the said sleeve is held in place and allowed to have a slight movement of rotation, 100 and also provided with the oppositely-inclined spur g^4 for engagement with the spur c^4 . The loose sleeve d^4 is also provided with a notch, h^4 , adapted to receive the head i^4 of the sliding bolt j^4 , which is held in its normal position by 105 means of the spring k^4 and is regulated in the extent of its movement by means of the milled nut l^4 .

The flange b^4 of the clutch-sleeve x^3 is also provided with a notch, m^4 , having a beveled 110 side, n^4 , and upon the projecting boss o^4 of the standard J is secured the spur p^4 , which is adapted to enter the notch m^4 of the flange b^4 , and serves by engagement with the incline n^4 of the notch to force the clutch-sleeve x^3 into 115 positive engagement with the spurs q^4 upon the clutch member z^3 , which is firmly keyed to the gear G . The flange b^4 is also held in the grooved shoe q^4 , pivoted to the bell-crank lever r^4 , which is held upon a stud, s^4 , located 120 at the base of the standard J , and to the lower outer end of the bell-crank lever is pivoted the pedal-lever t^4 , having the pedals $u^4 u^4$ at its opposite ends. The bell-crank lever r^4 is provided with a spur, v^4 , which engages with the 125 latch w^4 , pivoted to the side of the standard J and supported by the springs v^5 . The beveled outer end of the latch w^4 rests against the spur v^4 when the clutch-sleeve x^3 is at its disengaged position, thus serving to prevent accidental engagement and to support the weight of the 130 pedal-lever t^4 , above which at one end of the frame is placed the projecting stud y^4 , and at the same distance from the pivot joint of the

pedal-lever with the bell-crank lever and at the upper side of the said pedal-lever is placed the stud z^4 , and when it is desired to effect the engagement of the clutch members x^3 z^3 the said studs will form a fulcrum, by means of which the said pedal-lever will be made a lever of the second class and will cause the engagement of the clutch-sleeve from pressure upon the pedal at either side of the machine.

10 In operating the machine the leather is to be fed under the cutting-plungers at each side of the table B B', the cutter C being made slightly larger than the cutter C', thus producing heel-lifts of two sizes, the lifts formed by means of the larger cutter being adapted for the upper portion of the heel, while the smaller lifts are to be attached thereto, so as to form the lower portion of the same. The downward movement imparted to the sliding heads E E' will 15 first cause the raising of the valve u from its seat v by means of the projecting pin a^4 , which, by striking first upon the leather, will raise the valve and allow the paste to escape previous to the action of the lift-cutting mechanism, and the continued downward movement of the sliding heads will cause the holder Q to be brought down upon the upper surface of the pasted strip from which the lift is to be cut, thus clamping the leather firmly around the upwardly-projecting edge of the cutter, and during the continued downward movement of the sliding heads the holder Q will be firmly pressed against the leather at the outside of the cutter by means of the springs s s . The downward movement of the cutting-plunger, which is made in heel form to closely fit the heel-formed cutter, will cause the separation of a heel-lift from the pasted leatheren strip and the paste-supplying forcer R, which, after the cutting of the heel-lift, has a more extended downward movement than that of the cutting-plunger, by reason of the action of the arm p' , which strikes the spring U, link u' , weighted arm s' , and the connected arm t' , which is connected to the pasting-forcer R by means of the jointed clamp x' , and will thus serve to force the heel-lift downward into the carrier-opening z' . The heel-lift first deposited in the opening z' will rest in contact with the plane 20 upper surface of the bed A², which is under the carriers, and upon the continued reciprocation of the sliding heads of the machine an equal number of lifts may be deposited in the receiving-openings of the carriers Y Y', the forcer R being caused to make a gradually-decreasing downward movement by reason of the obstruction caused by the accumulated deposit of heel-lifts; and when the proper thickness of leather has been obtained the movement of the sliding heads is to be stopped by withdrawing the bolts i from under the vibrating arms M M', thus allowing the said arms to vibrate through the whole length of the slot b , so that a reciprocating movement will not be 25 thereafter imparted to the sliding heads E E', which heads may be caused to maintain their vertical position by the friction of the sides of

the clamp-bearings A³. Upon the proper filling of the carrier receiving-openings—one with the large and the other with the smaller sized heel lifts, as above described—and the disengagement of the lift-cutting mechanism the operator, by means of the pedal u^4 , effects the proper engagement of the clutch-sleeve x^3 with the opposite clutch member, z^3 , which is secured to the hub of the loosely-revolving gear G, which engagement will cause the shaft H to make one complete revolution, the clutch-sleeve x^3 becoming automatically disengaged at the exact completion of a single revolution by 30 reason of the contact of the inclined spur c^4 at one side of the axis of the clutch-sleeve with the inclined spur g^4 upon the side of the spring-operated sleeve d^4 , which sleeve at the initial contact of the oppositely-inclined surfaces of the spurs will partake of the rotary movement of the clutch-sleeve, and the bolt j^4 , the head i^4 of which is held in the notch h^4 of the said sleeve d^4 , will be carried back against the action of the spring k^4 until the regulating nut l^4 strikes the side of the lug o^4 , so that thereafter the sleeve d^4 cannot partake of the rotary movement of the clutch-sleeve, and then the incline of the spur g^4 of the sleeve d^4 will operate as a fixed cam to force the clutch-sleeve x^3 backward out 35 of engagement with the clutch member z^3 , which is keyed to the gear G, thus forcibly causing the disengagement of the clutch-sleeve x^3 to stop the movement of the cutting mechanism, whereupon the released sleeve d^4 will 40 be instantly brought back to its normal position by the action of the spring k^4 upon the bolt j^4 , the head of which is in notched engagement with the periphery of the said sleeve, thus returning the sleeve d^4 to its proper position for 45 renewed action upon the clutch-sleeve upon the subsequent engagement of the same to secure the renewed action of the cutting mechanism.

It may be observed that the object of imparting the above-described movement of the sleeve d^4 with the clutch-sleeve is to remove the spur g^4 from the point of disengagement of the clutch-sleeve by a backward movement, in order that the said clutch-sleeve may be thereafter moved into complete engagement 50 with its opposite clutch member without the obstructing engagement of the spurs c^4 and g^4 .

The engagement of the clutch-sleeve x^3 by causing a single revolution of the shaft H will also cause the corresponding revolution of the wheel B², which will operate to turn the wheel C² one-quarter of a revolution and to lock the same in its position, and the resulting movement of the shaft D² and gear d^2 will cause the pinion e^2 and the shaft V to make a semi-revolution, thus serving to bring another receiving-chamber under the cutters and to carry the previously-filled openings to a position in which their axes will be in line with each other in advance of the plunger I', and at the completion of the movement of the carriers through a space of one hundred and eighty degrees they will be locked in position by means of the flange a^5 of the wheel B², which enters the

socket b^5 of the wheel C^2 , and immediately upon the stopping of the revolution of the carriers the plunger I' will be caused to move upward by the action of the crank E' and connecting-rod H' upon the toggle-levers $F'G'$, thus serving to force the accumulation of smaller heel-lifts in the opening in the carrier Y' from the said opening into forcible contact with the accumulation of larger heel-lifts in the opening 10 of the carrier Y . At the initial forward movement of the carrier the rod r^2 , which rests in advance of the incline of the cam g^3 , will be raised, and then the friction-clamps v^2v^2 , which serve to frictionally hold the nail-wires at the 15 outer ends of the bifurcated arm u^2 , will be carried upward along the nail-wires, which at this time are being held between the forcing and cutting-off jaws a^3 and extend upward to the double reel k^2 , so that the said wires will 20 slip between the friction-clamps v^2v^2 as the said clamps are raised to a height sufficient to form the required length of nail, the pressure of the friction-clamps v^2v^2 being at all times constant, both at the upward and downward 25 stroke, and upon the continued movement of the shaft H the lever K' will be carried down to its lower position, in which the toe o^2 will be caused to strike against the lip p^2 , thus causing a slight upward movement of the sliding head l^2 , and the attached jaws a^3 , which are thus allowed to separate, will permit the wires to be fed downward by the pressure of the flat spring d^5 , which will force the rod r^2 downward into the recess c^3 , and thus, by 30 means of the friction-clamps v^2v^2 at the end of the attached bifurcated arm u^2 , carrying the length of wire previously measured off at the upward stroke of the said clamps downward between the opened jaws a^3 to form the two 35 nails required for securing the heel-lifts, the said nails being driven into the lifts while the said heel is being held in the chamber of the carrier. The upper carrier, Y , is thicker than the lower carrier, Y' , and the heel-lifts first 40 formed in the chamber of the said upper carrier fill but a fraction of the height of the same, and there will be left above the said heel-lifts in the said chamber a vacant space, into which the nail-wires will be projected, 45 and upon the further revolution of the shaft H the plunger I' will be caused to rise, thus forcing the smaller lifts in the chamber of the lower carrier, Y' , from the said chamber into the corresponding chamber of the upper carrier, Y , and the resulting upward movement 50 of the said heel-lifts by the plunger I' into the vacant space into which the wire to form the nails was first projected, as above described, and the conjoint downward movement of the 55 jaws a^3 within the inclined sides of the opening e^3 in the plate f^3 will cause the closing of the jaws upon the wire, and the slight downward movement of the said jaws after the closing of the same upon the wire, in conjunction 60 with the upward movement of the plunger I' to force the heel-lifts to the upper side of the chamber of the carrier Y , will cause the nails to

be driven into the lifts without the employment of an awl for the purpose of making a preliminary perforation for the same, and at the full 70 completion of the downward movement of the jaws a^3 the closing pressure of the inclined sides of the opening e^3 upon the correspondingly-inclined sides of the jaws will be sufficient to cause the wire to be cut off at the surface of the heel 75 by the angularly-sharpened termination of the said jaws, so that when cutting off the wire the said wire will be properly pointed for driving into the succeeding heel to be formed in the machine. The heel is held in a compressed 80 condition while the lifts are being cut to form another heel, and upon the re-engagement of the clutch-sleeve the initial movement of the shaft H will serve to withdraw the plunger I' from the chamber of the carrier Y' preparatory to the rotation of the carriers. When the carrier Y , which carries the finished heel, arrives at a certain position, so that the opening of the carrier is in line with the forcer-bar n^3 , the shoulder w^3 will strike against the arm v^3 , thus imparting movement to the arm l^2 and causing the arm r^2 to rise upon the incline of the cam i^3 , so that the end s^3 of the rod n^3 will rise into the chamber of the carrier and force the finished heel upward from the same. When 90 the shoulder w^3 has, owing to the eccentricity of the arm v^3 , become disengaged from the said arm by the continued movement of the carrier in making its semi-revolution, the arm r^2 having previously passed over the point 100 of the cam i^3 and been forced down back of the same by means of the spring p^3 , the action of the torsion-spring t^3 will cause the reverse movement of the arm l^2 to its former position for re-engagement with the incline of the said 105 cam in order to remove the succeeding heel from the carrier while the said carrier is in motion. It is to be understood, however, that when the carriers are provided with four chambers instead of two, as shown in my former 110 patent, No. 331,412, the chamber holding the finished heel will be brought to rest at an intermediate position, so that the discharging-forcer n^3 need not have a lateral movement, and in this case the upward movement of the 115 disengaging-forcer by suitable means will serve to eject the heel from the carrier.

The receiving-chambers of the carriers may be in some cases made of equal size. Therefore I do not limit myself to the unequal chambers 120 shown in the drawings.

I claim as my invention—

1. In a heel-machine, the combination, with a clutch mechanism which is adapted for automatic disengagement at the completion of one 125 revolution, of the operating-cam, the vibrating arm operated by the cam, the sliding head provided with a slot adapted to receive the vibrating arm, and a sliding bolt arranged transversely of the said slot and adapted to 130 effect the engagement or disengagement of the sliding head, substantially as described.

2. In a heel-machine, the combination, with the sliding head which serves to hold the cut-

ting-plunger, of the paste-cup provided with a cylindrical chamber, the paste-supplying tube having a side perforation, the spring-operated sliding sleeve adapted to force the paste 5 into the side opening of the tube from the cylindrical chamber, the paste-discharging valve, and means for causing the downward movement of the paste tube, substantially as described.

10 3. In a heel machine, the combination, with the sliding head which serves to hold the cutting-plunger, of the paste-cup provided with a cylindrical chamber, the paste-supplying tube having a side perforation, the spring-operated sliding sleeve adapted to force the paste 15 into the side opening of the tube from the cylindrical chamber, the paste-discharging valve, the force-head, the compound levers, and the spring for causing the continued downward movement of the force-head in advance of the cutting plunger, substantially as described.

20 4. In a heel-machine, the combination, with the rod *j*, shipper-arm *e*, and spring *r*, of the spring *m*, arm *f*, jointed to the sliding rod *h*, so as to allow said bar to have an independent vertical movement, and the bolt *i*, connected to the rod *h*, substantially as described.

25 5. In a heel-machine, the combination, with the sliding clutch-sleeve and bell-crank lever provided with a spur, of the spring-operated latch, the pedal-lever pivoted to the bell-crank lever, and the fixed fulcrum-pins, whereby the clutch-sleeve can be operated for engagement 35 from either side of the machine, substantially as described.

30 6. In a heel-machine, the combination, with the clutch mechanism which is adapted for automatic disengagement at the completion of one revolution of the shaft, of the wheel *B*, provided with the pin *b* and the flange *a*, the wheel *C*, provided with the slots *c*, shaft *D*, gears *d*, *e*, shafts *V* *V'*, connecting-gears *W* *W'*, and the interlapping carriers *Y* *Y'*, substantially as described.

45 7. In a heel-machine, the combination, with

the lapping carriers and means for operating the same, as described, of the reciprocating heel-compressing plunger, the cam-lever operatively connected with the said plunger, the bell-crank lever, the sliding head pivoted to the bell-crank lever, the cutting and holding jaws made tapering at their lower ends, the perforated plate adapted to cause the proper closing of the jaws, the wire-feeding clamps, and means for causing the feeding movement of the said clamps, substantially as described.

8. In a heel-machine, the combination, with the lapping carriers and means for operating the same, of the toggle-levers, the operating-crank, the pivoted head of the toggle-lever, the sliding head which incloses the pivoted head, the intervening spring, and the plunger, substantially as described.

65 9. In a heel-machine, the combination, with the lapping carriers and means for operating the same, of the toggle-lever, the operating-crank, the sliding head and plunger connected to the toggle-lever, the cam-lever connected to the joint of the toggle-lever, the pivoted bell-crank lever, the sliding head pivoted to the bell-crank lever, the cutting and holding jaws secured to the sliding head and made tapering at their lower ends, the perforated plate adapted to fit the tapering sides of the jaws, and the reciprocated feeding-clamp, substantially as described.

70 10. The combination, with the lapping carriers provided with receiving-chambers, of a plunger adapted to force the lifts from the chamber of one of the carriers into the chamber of the other, and the holding and cutting jaws which serve to point the wire and hold the same within the carrier-chamber, so as to be forced into the accumulated lifts by the advancing movement of the jaws and of the plunger, substantially as described.

ANTOINE J. LANGELIER.
